UNITED STATES PATENT OFFICE

ERIC OLLE SCHJOLIN, OF BIRMINGHAM, MICHIGAN, ASSIGNOR TO YELLOW TRUCK & COACH MANUFACTURING COMPANY, OF PONTIAC, MICHIGAN, A CORPORATION OF MAINE

REVERSED-FLOW WATER-COOLED ENGINE

Application filed February 18, 1928. Serial No. 255,409.

This invention relates to a cooling system for an internal combustion engine and has to do particularly with the cooling system of an internal combustion engine of an automotive vehicle.

It is an object of the invention to provide an improved circulating system for the cooling medium of an internal combustion engine. More specifically, it is an object of the invention to provide a cooling system which will provide a more even distribution of heat in the region of the cylinder heads.

Other objects and advantages of the invention will appear in the course of the following description, taken in connection with the accompanying drawing and appended claims.

In the drawing:

Figure 1 is a side elevation of a conventional internal combustion engine embodying my invention.

Figure 2 is a front view with parts broken away.

Referring to the drawing, I have illustrated in Figure 1 a conventional internal combustion engine including a cylinder block 10, water cover 12 and radiator 14. A water pump 16 is provided on the side of the engine and is driven in the usual manner from the crankshaft and is connected by means of an inlet pipe 18 with the lower part of the radiator and by an outlet pipe 20 with the water cover 12. A pipe 22 extending from the lower part of the water jacket of the cylinder block to the upper part of the radiator completes the circuit. Extending between the top of the water cover 12 and the top of the radiator 14 is a small pipe 24. This pipe is necessary to eliminate the possibility of the formation of an air pocket in the top of the water cover 12 and may be quite small, a three-eighths copper pipe being found to give good results. This pipe is so small that its interference with the normal flow of cooling liquid is negligible.

The structure described provides a more even distribution of heat in the cylinder block and thereby eliminates uneven expansion. This type of cooling system is particularly adapted for use with a sleeve valve engine, as illustrated, since this type of engine pre-

sents difficulties in the way of cooling. Forcing the water in at the top cools the junk heads and spark plugs efficiently and renders feasible a higher compression without any detrimental effects.

55

I claim:

1. In a circulatory cooling system for internal combustion engines for motor vehicles and the like, a main circuit including a heat radiating unit having an inlet and an outlet, a jacketed engine cylinder head connected with the outlet of the heat radiating unit, a jacketed engine cylinder block connected with the inlet of the heat radiating unit, and an auxiliary circuit comprising a by-pass around the jacketed head and block and connecting the jacketed head and the inlet of the heat radiating unit.

60 65 70

2. The structure of claim 1 and a pump for forcing cooling medium thru both the main circuit and the auxiliary circuit.

75

3. In a circulating cooling system for internal combustion engines for motor vehicles and the like, a closed circuit for cooling medium including a radiator having an inlet and an outlet, a jacketed engine cylinder block having an outlet connected with the radiator inlet, and a jacketed engine cylinder head having an inlet connected with the radiator outlet.

80 85 90

4. In combination a heat radiating unit having an inlet and outlet, a water jacketed engine comprising a cylinder block and a removable head affording a combustion chamber in which is located a spark plug, and connections between the lower portion of the block jacket and radiating unit inlet and between the radiating unit outlet and removable head jacket, whereby cool water from the radiating unit is introduced at the spark plug and hottest part of the engine.

95 100

5. In combination a heat radiating unit having an inlet and outlet, a water jacketed engine comprising a cylinder block and a head affording a combustion chamber in which a spark plug is located, an outlet connection between the lower portion of the block jacket and the inlet to the radiating unit, and a pump for withdrawing cold water from the

radiating unit outlet and delivering it under pressure to the head jacket for initial circulation through the head around the spark plug and thence through the head and back to the radiating unit.

5 In testimony whereof I affix my signature.

ERIC OLLE SCHJOLIN.
